UNITED STATES PATENT OFFICE.

HENRY JONATHAN LAWRENCE, OF LONGBEACH, CALIFORNIA.

WAVE-MOTOR.

No. 918,870.

Specification of Letters Patent. Patented April 20, 1909.

Application filed October 22, 1908. Serial No. 459,000.

To all whom it may concern:

Be it known that I, HENRY JONATHAN LAWRENCE, a citizen of the United States, residing at Longbeach, in the county of Los Angeles and State of California, have invented 5 a new and useful Wave-Motor, of which the following is a specification.

It is the object of the present invention to provide a wave motor so constructed as to 10 be operated directly through the impact of the waves.

A further object of the invention is to provide a wave motor including a wave impact member having an under surface presented 15 waveward so that the impact of the waves will act to raise the member, means being provided tending normally to lower the member.

A still further object of the invention is to 20 provide, in a wave motor, a wave impact member which is mounted for vertical oscillation and which has a convex under surface which is presented waveward.

Heretofore, in constructing wave motors, 25 it has been customary to embody the wave impact member in an oscillatory platform the free edge of which is presented shoreward so that the member will rise and fall with the waves, but I have found that by mounting 30 the wave impact member with the free edge presented waveward and likewise its under face, that a greater latitude of movement is provided for with the result that more work is performed by the motor. In connection 35 with such a wave impact member, I provide some suitable means which tends to lower the member so that after impact of each wave with the member, it is automatically, quickly, and with considerable force, swung 40 downwardly.

In the accompanying drawings, Figure 1 is a top plan view of the motor embodying 45 my invention, and Fig. 2 is a vertical longitudinal sectional view therethrough showing the manner of arranging the same.

In the drawings, there is illustrated a shaft 5 which is supported between suitable bearings 6, the shaft being fixed in the bearings, and carried by the shaft in such manner as to 50 permit of oscillation are arms 7 which are preferably in the nature of beams, the connection of the arms with the shaft being had by means of suitable clevises which are bolted to the inner end of the arms and 55 brace the shaft 5, it being understood that

the bearings 6 of the shaft are located upon the bed of the river or ocean in which the motor is arranged.

The ends of the arms which are connected to the shaft 5, are presented shoreward and 60 their opposite or free ends are presented in a direction which for the sake of convenience in describing the invention, will be termed waveward. The under sides of the arms 7 are convexed and tapered in the direction of 65 their free ends and secured to the under edges of the arms and connecting the same are a number of boards 9 which are placed edge to edge and extend in a continuous series from the free ends of the arms to a 70 point inwardly of said ends, the location of this latter point being determined by the character of the body of water in which the motor is placed, or in other words by the wave force. As before stated, the under 75 sides or edges of the arms 7 are convexed and the arms are tapered in the direction of their free ends so that in securing the boards 9 to the arms, a convex impact surface will be presented by the boards and the curvature 80 of the surface is such that an incoming wave will strike against the under sides of the boards 9, or in other words, against the convex wave impact surface which is presented by the boards, this surface being, as before 85 stated, presented waveward. A beam 10 is also connected with the shaft 5 in the same manner as are the arms 7 and this beam extends in the same general direction as the arms and substantially midway between the 90 same and above the boards 9, it being provided upon its under side with a spring 10' which acts as a buffer between the said beam 10 and the impact member. This beam 10 projects waveward beyond the free edge of the 95 wave impact member just described and between a pair of uprights 11 which are arranged beyond the said impact member and which are provided at their upper ends with a cap 12 supporting a pulley 13 and its bearings. 100 An eye member 14 is secured to the beam 10 at the outer end thereof and suspended loosely from the eye member is a weight 15, there being a power transmitting cable 16 also connected with the eye member and 105 trained over the pulley 13 in the direction of the shore. The weight 15 is preferably of such size that after the wave impact member and beam 10 have been oscillated or 110 swung in an upward direction and the wave

has receded they will quickly and with considerable force swing downwardly thereby drawing in a positive manner upon the cable 16. The cable 16, as before stated, is extended shoreward and is there connected with any suitable power converting mechanism.

As before stated, one of the salient features of my invention resides in so arranging the wave impact member that its under or impact surface will be presented waveward so that the impact of each wave will serve to elevate the member to the fullest possible extent thereby providing for a down stroke of longer duration than if the said surface was presented shoreward. I preferably provide upon the impact member two or more barrels or casks 17 which add buoyancy to the said member.

20. For convenience in designating the elements in the claims the impact member 9 and its supporting beam 7 will be termed the wave-oscillated impact member and the beam 10 will be designated the weight-controlled power member.

What is claimed is:—

1. In a wave motor, a wave oscillated impact member, and a weight controlled power member.

30. 2. In a wave motor, a wave oscillated impact member, a power member independent of the wave oscillated member, a weight supported by the said power member and tending to move the same in one direction of its movement, and a power transmission means connected with the said power member.

3. In a wave motor, a wave oscillated impact member, a power member, and a weight for imparting movement to the power member in one direction.

40. 4. In a wave motor, a wave oscillated impact member, a power member, and a weight carried by the power member and tending to move the member in one direction.

45. 5. In a wave motor, a wave oscillated impact member, a power member, and a weight connected with the power member and tending to lower the same.

50. 6. In a wave motor, a wave oscillated member, a power member, a weight supported beyond the power member and tending to lower it, and a power transmission

means connected with the weight supporting means.

7. In a wave motor, a wave oscillated member, said member presenting a convex surface, and a power member having a normal tendency to lower.

8. In a wave motor, a wave oscillated member presenting a convex surface, a power member, and a weight supported beyond the power member and tending to lower the same.

9. In a wave motor, a wave oscillated member having a curved body presenting a convex impact surface, a power member, and means tending to lower the power member.

10. In a wave motor, oscillatory arms, an impact member supported by the arms for oscillation therewith, a power member, and means supported from the said power member tending to lower the same.

11. In a wave motor, a wave oscillated member, an oscillatory power means independent of the said member and adapted to be oscillated thereby in one direction, and means tending to oscillate the said power means in an opposite direction.

12. In a wave motor, an oscillatory wave impact member, an oscillatory power means adapted to be moved in one direction through the oscillation of the impact member, and means connected with the power means tending to move it in the opposite direction.

13. In a wave motor, an oscillatory wave impact member, an oscillatory power means adapted to be oscillated in one direction through the oscillation of the impact member, and a weight supported at the end of the power means and tending to oscillate the said means in an opposite direction.

14. In a wave motor, an oscillatory wave impact member, an oscillatory power means extending above the member and adapted to be lifted through the oscillation thereof, and means tending to lower the said power member.

In testimony that I claim the foregoing as my own, I have hereto affixed my signature in the presence of two witnesses.

HENRY JONATHAN LAWRENCE.
